UNITED STATES PATENT OFFICE.

MARTIN V. B. PABOR, OF FREDERICKTOWN, MISSOURI.

DESIGN FOR A RACK.

SPECIFICATION forming part of Design No. 25,439, dated April 28, 1896.

Application filed March 10, 1896. Serial No. 582,657. Term of patent 14 years.

To all whom it may concern:

Be it known that I, MARTIN VAN BUREN PABOR, of Fredericktown, in the county of Madison and State of Missouri, have invented and produced a new and original Design for a Rack, of which the following is a full, clear, and exact description.

This invention relates to racks adapted for supporting hats or other apparel, and also for receiving cards.

Reference is to be had to the accompanying drawing, forming a part of this specification, which shows a front view of a rack embodying my new design.

The leading feature of my design consists in the rack having in general the shape of a Maltese cross with a diamond-shaped panel in the center, the angles of the panel being disposed toward the arms of the cross.

Another prominent feature of the design resides in the ornamentation of the arms of the cross, which consists in the rods *a*, having knobs *b*, the knobs being disposed in lines parallel with the sides of the diamond figure.

Other features of the design reside in the hooks *c* of ornamental shape, disposed on the several arms of the cross, and the shelf *d* suspended along the edge of the lower arm by chains *e*.

I claim—

The design for a rack herein shown and described.

MARTIN V. B. PABOR.
